UNITED STATES PATENT OFFICE.

WILLIAM B. REED, OF WESTFIELD, MASSACHUSETTS, ASSIGNOR TO THE H. B. SMITH COMPANY, OF WESTFIELD, MASSACHUSETTS, A CORPORATION OF MASSACHUSETTS.

FURNACE.

Application filed October 8, 1923. Serial No. 667,091.

To all whom it may concern:

Be it known that I, WILLIAM B. REED, a citizen of the United States of America, and resident of Westfield, in the county of 5 Hampden and State of Massachusetts, have invented new and useful Improvements in Furnaces, of which the following is a specification.

This invention pertains to so-called 10 smokeless furnaces, relating more particularly to furnaces for hot water and low pressure steam heating boilers.

The principal object of the invention is 15 to improve the construction of such furnaces in the manner hereinafter more particularly described and pointed out in the claims.

In the accompanying drawings, a preferred embodiment of the invention is illustrated by way of example, and in such drawings:—

Fig. 1 is a perspective view of a furnace embodying the present invention, a portion 20 of its side wall being broken away to show details of the interior construction;

Fig. 2 is a rear end elevation of the furnace, a portion of the rear wall being broken away;

Fig. 3 is a longitudinal vertical section 30 through a furnace embodying the present invention, certain parts being shown in elevation;

Fig. 4 is a perspective of the base section 35 of such a furnace, the upper portion being removed;

Fig. 5 is a front elevation, partly in vertical section, of a preheater device forming an element of the present invention;

Fig. 6 is a plan view of the device shown 40 in Fig. 5; and

Fig. 7 is a fragmentary vertical section to larger scale, of the upper part of one of the preheater tubes shown in Fig. 3.

Referring to the drawings, the numeral 1 45 indicates in general a furnace of usual construction but embodying the novel features constituting the present invention. This furnace comprises the fire box 2, the grate 3, and the ash pit 4 beneath the grate. At the rear of the grate a bridge wall or fire back 5 of any usual construction is arranged. This bridge wall is provided with one or more windows or openings 6 for the passage of the volatile or gaseous products of combustion.

A combustion chamber 7 is located to the rear of the bridge wall or fire back 5. Below the combustion chamber an air supply pit, separate from the ash pit, or chamber 8 is provided. This air supply pit or chamber 60 is furnished with an air inlet opening 9 in one of its walls controlled by a damper 10. Connections 11 extend from the damper to a handle 11^a conveniently located at the front of the furnace. 65

A metal plate 12 constituting an element of an air preheater separates the combustion chamber 7 from the air supply chamber 8. This plate preferably is turned up at its opposite edges 13 and 14 respectively to 70 provide a shallow, pan-like receptacle. A slab or layer 15 of fire-resistant material such, for example, as fire clay, sand, slag or the like is arranged upon the plate 12 to protect the latter from the intense heat of 75 the combustion chamber.

The plate 12 is furnished with a series of openings or apertures, preferably adjacent to its forward edge and preferably disposed in two parallel rows, although a greater or 80 lesser number of rows of openings may be provided. The lower end of a tube 16 of heat conducting material such for example as cast iron is disposed in each of the apertures in the plate 12, the lower ends of the tubes communicating freely with the air supply chamber 8. The top of each tube is furnished with one or more air delivery orifices 19, while the side walls of each tube near its upper end are provided with small 85 orifices 20. These orifices in the end and sides of the tube are so designed that the principal part of the air discharged is emitted near the extreme upper end of the tube. 90

A convenient construction illustrated in the drawings employs hollow caps 18 for closing the upper ends of the tubes. These caps are preferably of hexagonal contour so that they fit snugly against each other thus utilizing the available space to the best advantage and also keeping the tubes in proper relative position, and are furnished with downwardly extending nipples 18^a which fit within the tubes. 95

The orifices 19 are formed in the upper wall of the hollow cap and also in tapering bosses 18^b projecting therefrom. Additional orifices 19^a are provided in the lower wall of the cap if desired. While hexagonal 100 105 110

caps are desirable for the purpose, it is contemplated that apertured closures of other form may be employed, or that a unitary header may be provided for the entire series 5 of tubes, but in all cases it is desirable to stagger orifices in the ends of adjacent tubes.

The preheater unit thus constructed is positioned within the combustion chamber in the manner indicated in Fig. 3, so that 10 the bank of tubes 16 is disposed substantially parallel to the bridge wall 5 and with the air delivery apertures substantially at the level of the windows or openings 6 in the bridge wall.

15 In a furnace, part of the combustion takes place in the fire bed upon the grate and part in the combustion space or chamber. The burning fuel bed acts as a gas producer or retort wherein a portion of the solid fuel 20 is distilled. The gases rising from the fuel bed thus contain a high percentage, varying according to the fuels supplied, of volatile combustible with insufficient free oxygen to burn it. Hence to burn these 25 gases completely and eliminate smoke, air must be admitted and mixed with the volatile or gaseous combustible. The necessary amount of air for complete combustion can not be supplied through the grate, as the 30 rate at which gas is evolved from the coal in the fuel bed increases in direct proportion to the amount of air passing through the grate, the amount of unconsumed combustible in the gases rising from the fuel 35 bed remaining substantially the same, and if the great volume of air necessary for complete combustion be admitted over the fuel bed by opening the fire doors or leaving the dampers in such doors open the heating 40 surfaces of the boiler are rapidly cooled, greatly reducing the efficiency of the boiler as a water heating instrument.

In accordance with the present invention substantially uniform results and practically 45 complete combustion of the gaseous constituents of fuel high in volatile matter are secured without requiring any especial skill on the part of the fireman. In the device herein disclosed, the volatile products of 50 combustion rising from the bed of fuel upon the grate 3 pass rearwardly through the windows or openings 6 in the bridge wall 5 and swirl laterally and downwardly about the bank of pipes 16 which are thus highly 55 heated and warm the air within them.

This heated air escapes through the apertures in the pipes in the form of a multitude of filament-like streams or jets into the upper part of the stream of gas passing 60 over the bridge wall. As the incoming air, although hot, is not as hot as such gas, the fine filaments of air emitted from the orifices tend to descend through the gaseous stream and to mingle intimately with the 65 latter so that the preheated atmospheric

oxygen immediately unites with the gaseous combustible completely oxidizing the latter with the result that substantially no particles of carbon or soot remain. This action also produces an extremely high temperature in the combustion space 7 from which the incandescent gas flows through suitable passages provided between the heating pipes of the boiler, thus rapidly raising the temperature of the water. The exhaust gases then pass through suitable flues, to the chimney.

The preheating unit illustrated in Fig. 5 is of simple and durable construction, and relatively cheap to manufacture, so that its replacement if necessary is not a substantial item in the cost of operation, while it is readily applicable to furnaces of other construction with but slight change.

While in the present instance the tubes 80 16 have been shown as vertically disposed, it is contemplated that they may be arranged in some other manner and that a greater or lesser number of tubes may be 85 employed as circumstances may warrant.

90 I claim:

1. A furnace of low pressure type having a combustion chamber and an air inlet pit below it, an apertured metallic plate separating the chamber and pit, a coating of fire resistant material upon the upper surface of the plate, and a series of tubes each seated at its lower end in an aperture in the plate and opening into the air inlet pit, said tubes having air discharge orifices in their lateral walls adjacent to their upper ends.

95 2. In combination with a furnace of low pressure type, an air preheater comprising a metallic plate having its opposite edges bent upwardly, the plate having a series of apertures adjacent to one edge, a tube seated at one end in each of said apertures and provided with a plurality of small discharge orifices adjacent to its other end, and fire 100 resistant material covering the plate between its upturned edges.

105 3. A furnace of low pressure type comprising a grate and an ash pit below it, a combustion chamber to the rear of the grate, an apertured bridge wall separating the space above the grate from the combustion chamber, an air inlet pit to the rear of the ash pit and separated therefrom, a metallic partition between the air inlet pit and combustion chamber, and air preheating means 110 carried by the partition comprising a series of parallel, vertical metallic tubes closed at their upper ends and having orifices in the upper portions of their side walls and at their upper ends arranged to deliver a 115 plurality of jets of heated air into the combustion chamber.

120 4. In combination with a furnace of low pressure type, an air preheater comprising a plurality of rows of tubes open at one end 125

to an air inlet chamber, and caps closing the opposite ends of the tubes, said caps having discharge orifices therein, orifices of adjacent caps being staggered.

5. In combination with a furnace, an air preheater comprising a plurality of rows of metallic tubes communicating at one end with an air supply, and hexagonal caps closing the opposite ends of the tubes, said 10 caps engaging one another to hold the tubes in proper relative position, the caps being provided with air delivery openings.

6. In combination with a furnace, an air preheater comprising a row of tubes communicating at one end with an air supply, and caps closing the opposite ends of the tubes, the caps having air delivery orifices therein and the tubes having delivery orifices in their lateral walls adjacent to the 15 caps.

7. A furnace of the low pressure type comprising a grate, a combustion chamber to the rear of the grate, a bridge wall sep-

arating the grate and combustion chamber, said wall having apertures for the passage 25 of heated gases, an air inlet chamber below the combustion chamber, a horizontal metallic partition separating the air inlet and combustion chambers, heat insulating material protecting the upper surface of said 30 partition, the latter having series of openings therethrough, tubes of heat conducting material having their lower ends seated in the respective openings, each tube having a plurality of orifices in the upper part of its 35 side wall, and a hexagonal cap closing the upper end of each tube, said caps being of larger diameter than the tubes and having orifices in their tops and also in their undersides where they overlap the tubes, the caps 40 of adjacent tubes engaging each other to hold the tubes in parallel relation.

Signed by me at Westfield, Mass., this (1st) first day of October 1923.

WILLIAM B. REED.
